UNITED STATES PATENT OFFICE.

SIDNEY S. GRIFFIN, OF DETROIT, MICHIGAN.

COASTER STEERING GEAR.

Application filed January 6, 1925. Serial No. 893.

To all whom it may concern:

Be it known that I, SIDNEY S. GRIFFIN, a citizen of the United States, residing at Detroit, in the county of Wayne and State 5 of Michigan, have invented certain new and useful Improvements in Coaster Steering Gears, of which the following is a specification.

This invention relates to combined sled 10 and coaster toys and has for its primary object the provision, in a manner as herein-after set forth, of a toy of this type wherein the same may be used as a sled, having runners therefor, or the runners may be 15 quickly and easily removed to lower the device upon wheels permanently carried thereby.

Another object of the invention is the provision, in a manner as hereinafter set forth, 20 of a coaster device having an improved type of steering mechanism for controlling the same.

Still another object of the invention is the provision, in a manner as hereinafter set 25 forth, of a convertible sled or roller coaster device having an improved steering mechanism for controlling the front wheels or runners therefor, and being of strong and durable construction, light in weight, of neat 30 and attractive appearance and inexpensive to manufacture and assemble.

The invention will be best understood from a consideration of the following detailed description taken in connection with 35 the accompanying drawings forming a part of this specification, with the understanding that the invention is not confined to any strict conformity with the showing of the drawings, but may be changed and modified 40 so long as such changes and modifications mark no material departure from the salient features of the invention as expressed in the appended claim.

In the drawings,

45 Figure 1 is a side elevation of the toy embodying this invention.

Figure 2 is a bottom plan view of the same.

50 Figure 3 is a transverse section taken upon the line 3—3 of Figure 1, and,

Figure 4 is a transverse section taken 55 upon the line 4—4 of Figure 1.

Referring now to the drawings in detail wherein like numerals of reference indicate corresponding parts throughout the several views, the body or platform of the coaster

is indicated at 1 and as shown, is of substantial length and width.

Secured to the under side of the platform upon the longitudinal center thereof, is a 60 short block or cleat 2, the front end of which is flush with the front edge of the platform and extends backwardly a short distance therefrom.

Extending transversely of the under side of the body at the front and rear, are traction element carrying frames, each comprising an outer frame 3 of substantially U-shaped conformation as shown, and an inner frame 4 of less width than the outer frame and also of substantially U-shaped conformation. These frames are secured in inverted position upon the under side of the platform, the yoke of the smaller frame 4 fitting against the inner face of the yoke of the larger frame 3, as clearly shown in Figures 3 and 4, and the two are securely bolted to the body of the device by means of a central bolt 5 and nut 6.

It will be noted that the front traction element carrying frame is secured across the cleat 2 and not directly to the under face of the body 1, as is the rear frame, and as the frames are of substantially the same height, this construction normally raises the 75 forward end of the sled to a higher point than the rear portion thereof.

The depending legs of the two U-shaped members, which make up the front and rear traction element carrying frames are parallel and spaced apart as shown, and have secured therebetween, by means of the pivot pins or bolts 7, the roller members 8. These roller members are of course removable from between the legs of the frame in which 95 they are held.

The bolt 5 which secures the front frame to the under side of the cleat 2 is the only securing means between the front traction element carrying frame and the body of the device, and this bolt acts as a king bolt or pivot for the front frame, whereas the rear frame has additional bolts 9 which pass through the body of the platform 1 and secure the extremities of the yoke of the member 3 which forms a part of the rear frame.

Carried upon the inner end of each of the bolts 7 is a depending bracket member 10, the lower end of each of which extends a substantial distance below the wheels or rollers 110 8 and is outturned beneath the rollers to provide the foot 11. Each of these feet 11

has secured thereto and carries a runner member 12, which fits the device for traction upon snowy or icy surfaces. It can readily be seen that these runners may be easily and quickly removed, when it is desired to use the device as a roller coaster.

At the front end of the coaster there is positioned a substantially U-shaped yoke member 13 having the legs thereof extended one across the top of the platform 1 and the other beneath the under side of the cleat 2 and pivotally secured in position by means of the bolt 14 which extends through the two legs and through the body and cleat, as shown in Figure 1. The looped end of the yoke 13 is positioned a substantial distance beyond the front end of the coaster and is adapted to be swung laterally, the legs pivoting upon the bolt 14.

The outer end or head of the yoke 13 has secured against the face thereof a vertically positioned steering post 15, there being interposed between the abutting faces of the post and the head of the yoke a plate 16. As shown in Figure 1, the post is secured to the yoke 13 at a point adjacent its lower end, leaving a small portion thereof extending below the yoke and the lower end of the post has secured to one side face a plate 17, the lower end of which is turned outwardly as at 18 and flush with the lower end of the post as shown. Connecting this outturned end 18 with the front traction element carrying frame is a link member 19, which is adapted to cause the front traction element bearing frame to swing upon the central bolt 5 which retains it in position upon the under side of the sled, when the steering post is swung laterally upon the pivot pin 14 which secures the yoke 13 to the sled. The upper end of the steering post 15 is provided with the usual cross arms 20

which serve as hand grips for the occupant of the device.

It will be readily seen that when an occupant desires to steer the coaster, he exerts pressure upon one or the other of the hand grips 20 carried by the steering post to cause the post and the yoke 13 to swing across the front end of the coaster toward one side or the other and when this move is made the connecting link 19 will swing the front traction element carrying frame upon its pivot and thereby guide the coaster in the desired direction.

From the foregoing description it will be readily seen that there has been provided a coaster device of unique design and having a steering apparatus of an improved and sturdy structure.

Having thus described my invention what I claim is:

In a coaster toy of the character set forth, including a body provided with front and rear supporting traction elements, a substantially U-shaped member having the legs of substantial length and having the ends thereof arranged one upon the upper side and the other beneath the lower side of said body at its forward end, a pivot bolt passing through said body and said legs, a steering column secured adjacent its lower end to the yoke of said member, a right angled bracket having one leg thereof secured to one side of said column and the other leg extending at right angles to and from the lower end of the column, and a steering connecting link attached at one end to said other leg and connected with and controlling said front traction element.

In testimony whereof, I affix my signature hereto.

SIDNEY S. GRIFFIN.
